WINDOW SASH CONSTRUCTION

Edward F. Chaffee, Syracuse, N. Y., assignor to
 The O. M. Edwards Company, Inc., Syracuse,
 N. Y., a corporation of New York

Application July 15, 1936, Serial No. 90,737

5 Claims. (Cl. 189—64)

This invention relates to window sash constructions for vehicles, such as railway cars, and has for its object a mounting for the sash by which the sash is frictionally mounted in the window frame and capable of edgewise shifting within limits to relieve the glass pane of the force of jerks and shocks and strains occurring when the vehicle or car is more or less suddenly stopped or started.

10 It further has for its object a window construction for vehicles, as railway cars, which are streamlined and the window sashes are so mounted that their outer faces are nearly flush with the outer surface of the car body.

15 It further has for its object a simple and compact means for frictionally holding the sash in the window frame in such a manner that it is capable of edgewise shifting movement within limits.

20 Other objects will appear throughout the specification.

The invention consists in the novel features and in the combinations and constructions herein-after set forth and claimed.

25 In describing this invention, reference is had to the accompanying drawings in which like characters designate corresponding parts in all the views.

Figure 1 is a fragmentary elevation of a window structure embodying this invention.

Figure 2 is a fragmentary sectional view on line 2—2, Figure 1.

Figure 3 is a sectional view on line 3—3, Figure 1.

25 Figure 4 is a fragmentary detail view of a single sash construction embodying this invention.

In streamline trains, which are air conditioned, the window sashes are stationary. Heretofore, it has been customary to attach the sash in the window opening or window frame with screws from the outside. These screws present a more or less unsatisfactory appearance and require numerous holes in the frame and in the sash.

40 One of the principal features of this invention is a compact means for holding the sash, either single or double, in position, which holding means is concealed and not exposed on the outside of the car and located for the most part beyond the edges of the sash. Further where the sashes are attached rigidly to the car body posts or frames any strains set up by sudden impact (such as contact with bumping posts or in coupling the cars together) are transmitted direct to the sashes with consequent damage to glass and sash

frames, hence it is desirable to have the sash structure held yielding in the opening.

1 designates generally the frame which may be an integral part of the car body structure or a separate frame, it being usually an integral part of the car structure around or confining the window opening. The frame or the car body is usually formed of sheet metal and also formed so as to provide a channel C around the window opening with the open side of the channel presented toward the window opening. It is in this channel that the sash frame or frames extend.

2 designates the outer sheet metal plate of the window frame; 3 a second plate annular in cross section with a flange 4 lying against the inner 15 face of the plate 2 and with a flange 5 spaced apart from the plate 2 and forming a surface for the interior trim of the car. These plates are usually an integral part of the car body structure.

6 is a sill mounted on the intermediate part 20 of the plate 3 and forming the side of the channel opposed to the outer side formed by the plate 2 and flange 4.

25 In Figures 1, 2 and 3, a double sash is shown. The double sash construction has all features of the single sash construction shown in Figure 4 particularly, in so far as the clamping strip for holding one of the double sashes or the single sash in the channel of the frame is concerned.

30 One of the principal features of the invention is the means by which the glass pane is yieldingly mounted and also frictionally mounted in the window frame, so as to shift within limits in an edgewise direction. Each sash, as here shown, includes a glass pane and the mounting therefor, which is a sash frame slidably or frictionally mounted in the window opening or window frame with a portion or flange on one side thereof frictionally engaging one side wall of a 35 channel formed in the frame, where it is frictionally held by clamping means. The channel in the frame extends entirely around the sash and is of such depth that the sash frame is capable of shifting edge wise in any direction 40 under the influence of jerks or shocks, so that the glass pane is relieved to a large extent of the force of the shocks and jerks.

45 In Figures 1, 2 and 3, the sash construction includes outer and inner sashes designated generally 11 and 12, each including a metal sash frame usually of extruded metal and designated respectively 13 and 14. The extruded frame members may be of any suitable cross section, and, as here shown, the outer side of the outer sash frame 13 50

55

presses against the plates 2 and 4 of the window frame, the sash frame being formed with a circumferential flange 18, which thrusts against the outer wall of the channel C. The flange 4 of the window frame member 3 terminates at its edge short of the inner edge of the plate 2 leaving a rabbet, and the sash frame 13 is formed with a jog 16 seated in the rabbet. The glass pane of the sash seats in a U-shaped sealing strip 17 of yielding material, as rubber, located in a channel in the sash frame 13, the inner side of the channel being removable and being in the form of a glazing strip 18, one margin of which seats in a groove 19 formed in the sash frame 13.

15 The means for frictionally holding the sash frame 13 in position is one or more clamping strips 21 extending lengthwise of the rails and stiles of the sash and located in the channel C, this strip being fulcrumed at one edge at 22 on the bottom of the channel C, that is, on the intermediate part of the plate 3, and having its opposite margin or flange 24 pressing toward the inner face of the sash frame 13, this strip being clamped in position by screws 25 extending through the intermediate part of the strip between the fulcrumed edge 22 and the flange 24 and threading into the bottom of the channel. Preferably, as here shown, this strip is Z shaped in general form in cross section with the edge 30 of one arm of the Z formation fulcruming at 22 and the other arm, as 24, pressing flatwise against the sash frame 13, and the screws 25 extend through the intermediate part of the Z formation.

35 The inner sash 14 is of similar construction but is provided with a marginal flange 26 corresponding to the flange 18 coacting with or engaging the edge of the sill 6 provided at one side of the channel C and with the glazing strip 27 corresponding to the glazing strip 18 located on the side of the sash frame 14 toward the sash frame 13. The flange 24 of the securing strip therefore is interposed between the sash frames and preferably a strip 28 of compressible and absorbent material is folded over the flange in order to be interposed between the sashes, so that the fold is exposed in the space between the sashes. This serves to absorb moisture from between the sashes to prevent clouding and frosting, when other dehydrating means is not employed.

50 The inner sash 14 is firmly secured in the channel C by being clamped to the outer sash by means of screws 31 extending through the corner portions of the sash frames, the screws extending through an opening in the inner sash and threading into the outer sash, as seen in Figure 3. In order to permit the ready removal of the inner sash, these screws are studs, and the opening 33 in the inner sash frame 14 is large enough to permit the head of the stud to pass therethrough. A locking means in the form of a pivoted latch 35 is provided movable into a position between the head of the stud and the inner sash frame 14.

55 In Figure 4 is illustrated a single sash construction, wherein the clamping strip 41 corresponding to the strip 21, although Z shaped in general form is of slightly different contour from that shown in Figure 2, in that the intermediate part of the Z formation is considerably wider with respect to the flange 42, corresponding to the flange 24. Also, this strip extends into a recess in the sill, and the sill must be removed in order to give access to the clamping screws 45, corresponding to the screws 25.

75 In the form shown in Figure 4, the strip, in-

stead of coacting with the face of the sash, coacts with the circumferential flange 15 of the sash frame.

The window frame and sash are here shown as provided with rounding corners and the window frame includes corner pieces 50 formed with rounding channels forming continuations of the channels C formed by the sheet metal plates 2, 3.

Clearances 51 and 52 are provided between the extreme edges of the sash frames and the bottom of the channel in the window frame and between the base of the flange which presses against the outer side of the channel C and the continuous edge of the wall of the car body forming the window opening, those clearances permitting the sash to shift edgewise when frictionally clamped in position to relieve the sash of the glass pane of sudden shocks tending to break the glass pane.

In either embodiment of the invention, the sash frame is held in position by a strip fulcrumed at one edge having its margin remote from the fulcrum pressing against the sash and is held in position or moved about its fulcrum to clamp it against the sash frame by a screw passing through the intermediate part of the strip and threading into the window frame. Also, this clamping strip in either embodiment of the invention is located or concealed in a channel located at the edges of the sash frame.

What I claim is:

1. In combination with a window frame formed with a channel, of a window sash mounted in the channel with one side face against one side of the channel, and means located in the channel coacting and pressing against the other side face for clamping the sash in the frame, said means comprising a strip located entirely in the channel beyond the edge of the glass pane of the sash, the strip being fulcrumed at one edge on the bottom of the channel and having its margin remote from the fulcrum pressing against the sash, and a screw extending through the strip against its fulcrumed edge and said margin and threading into the bottom of the channel.

2. The combination with a window frame, of a window structure comprising a double sash, one sash being mounted with one side face against the frame, and means coacting and pressing against the other side face for clamping the same in the frame, said means comprising a strip substantially Z-shaped in cross section with one of the arms of the Z pressing against the other side face of the sash and the edge of the other arm of the Z fulcruming on a portion of the frame, and clamping means extending through the intermediate part of the Z strip and coacting with the adjacent portion of the frame and tending to tilt the strip about its fulcrumed edge and clamp the strip against the sash, the second sash being mounted in the frame and thrusting against the arm of the Z strip which clamps the first sash in position, whereby said arm of the Z strip is interposed between the sashes, and means for securing the second sash in the frame.

3. The combination with a window frame, of a window structure comprising a double sash, one sash being mounted with one side face against the frame, and means coacting and pressing against the other side face for clamping the same in the frame, said means comprising a strip substantially Z shaped in cross section with one of the arms of the Z pressing against the other side face of the sash and the edge of the other arm of the Z fulcruming on

a portion of the frame, and clamping means extending through the intermediate part of the Z strip and coacting with the adjacent portion of the frame and tending to tilt the strip about its fulcrumed edge and clamp the strip against the sash, the second sash being mounted in the first sash in position, whereby said arm of the Z strip is interposed between the sashes, and means for securing the second sash to the first 10 sash and clamping the same against the interposed strip.

4. The combination with a window frame formed with a channel facing the window opening, of a window sash extending in the channel and mounted with one side face against one 15 side wall of the channel, means coacting with and pressing against the other side face of the sash for clamping the sash in the frame, said means including a strip located in the channel and extending lengthwise along the stiles and rails of the sash, and means for securing the strip in the channel, a second sash mounted in the frame with one side face thrusting against the said strip, and means connecting the sashes 20 for clamping the second sash toward the first sash and against the strip, and a sealing strip of compressible, moisture absorbent material interposed between the sashes and the strip and having a portion exposed in the space between 25 the sashes.

5. In a window construction, the combination with a window frame formed with a channel facing the window opening, of a window sash comprising a marginal frame and a glass pane yieldingly mounted therein, the sash frame slidably and frictionally coacting with the window frame and capable of shifting in an edgewise direction under the force of shocks, means for clamping the sash frame in frictional engagement with the window frame in a direction cross-wise of the edgewise movement, said means pressing on one side of the sash frame to press the other side into frictional engagement with one side of the channel of the window frame, including a strip located in the channel and extending lengthwise along the stiles and rails of the sash, means for securing the strip in the channel, a second sash mounted in the frame with one side face thrusting against said strip, and means connecting the sashes for clamping the second sash toward the first sash against the strip, all whereby both sashes are capable of sliding edgewise, as a unit, under shocks and are braked in their sliding movement by the frictional engagement of the first sash with one 25 wall of the channel and frictional engagement of the other sash with said strip by reason of it being clamped to the first sash.

EDWARD F. CHAFFEE. 30
